CHARLES HALASKA

INVENTOR

Victor J. Evans

ATTORNEY

UNITED STATES PATENT OFFICE.

CHARLES HALASKA, OF MILWAUKEE, WISCONSIN.

BASKET.

1,423,419.

Specification of Letters Patent. Patented July 18, 1922.

Application filed January 15, 1921. Serial No. 437,470.

To all whom it may concern:

Be it known that I, CHARLES HALASKA, a citizen of the United States, residing at Milwaukee, in the county of Milwaukee and 5 State of Wisconsin, have invented new and useful Improvements in Baskets, of which the following is a specification.

This invention relates to baskets or receptacles and an object of the invention is to 10 provide a sheet metal receptacle particularly designed for use as a clothes basket when hanging up clothes to dry or taking them down after drying, as a tub for washing clothes, bath tub for children or analogous 15 uses.

Another object of the invention is to provide a sheet metal basket or receptacle as specified which is provided with a cover to protect the contents of the basket from 20 dust, dirt, or other foreign matter and also to reinforce the sides of the basket and cover by ribs which are struck from the sides and top respectively.

Other objects of the invention will appear 25 in the following description and in the accompanying drawing wherein:

Fig. 1 is a side elevation of the improved basket.

Fig. 2 is a top plan of the basket with 30 the cover removed.

Fig. 3 is a longitudinal vertical section through the basket.

Fig. 4 is a top plan of the cover of the basket.

Fig. 5 is an enlarged detail section 35 through one corner of the basket and taken on the line 5—5 of Fig. 3.

Referring more particularly to the drawings, the body 1 of the basket is constructed 40 of sheet metal treated to prevent rusting thereof, and it is preferably stamped from

a single piece of sheet metal having its upper edge rolled outwardly as at 2 while its sides are provided with vertical reinforcing ribs 3 at the corners of the basket or retainer. 45 The ribs 3 are struck outwardly from the sides of the body 1 and lend rigidity to the sides. Handles 10 may be attached to the body 1.

A cover 4 for the body 1 is provided which 50 cover is also constructed of sheet metal and is bent back upon itself at its edge as at 5 to provide an annular shoulder for engagement with the rolled edge 2 of the body 1 and also to provide a flange 6 for frictional 55 engagement with the inner surface of the sides of the body 1. The flange 6 of the cover 4 is provided with outstruck reinforcing ribs 7 for registration with the ribs 3 of the body 1 and the cover 4 is also provided with outstruck ribs or corrugations 8 which radiate from the center of the cover and a handle 9 is attached to the outer surface of the cover at its center.

It is, of course, to be understood that the 65 invention may be constructed in various other manners and the parts associated in different relations and, therefore, I do not desire to be limited in any manner except as set forth in the claim hereunto appended. 70

Having thus described my invention what I claim is:

As a new article of manufacture, an oval basket constructed of sheet metal and having outstruck reinforcing ribs at each end equidistant of the center and extending through 75 the full height of the basket, a cover and outstruck ribs radiating from the axis of said cover and adapted to register with the ribs on said basket. 80

In testimony whereof I affix my signature,
CHARLES HALASKA.
